UNITED STATES PATENT OFFICE.

HERMAN TAPPAN, OF NEW YORK, N. Y.

DESIGN FOR A PERFUME-HOLDER.

SPECIFICATION forming part of Design No. 19,843, dated May 13, 1890.

Application filed February 26, 1890. Serial No. 341,886. Term of patent 3½ years.

To all whom it may concern:

Be it known that I, HERMAN TAPPAN, of the city, county, and State of New York, have invented and produced a new and original Design for a Perfume-Holder, of which the following is a full, clear, and exact specification.

Reference is to be had to the accompanying drawings, forming a part of this specification, in which the figure represents a side elevation 10 of the design.

The leading feature of the design consists in a globus A, which is spherical in outline, with top and bottom slightly flattened, and having an ornamental base and top. From 15 the bottom of the sphere extends downward

an ornamental base B, and on the flattened top are arranged a series of connected fields C, from the top of which extends upward a cylinder D, forming the neck of the holder. On the upper end of the cylinder D is arranged an ornamental bow E, from which extends upward a cone-shaped cap F.

I claim—

The design for a perfume-holder herein shown and described.

HERMAN TAPPAN.
